UNITED STATES PATENT OFFICE.

THOMAS P. AITKIN, OF MANCHESTER, CONNECTICUT.

COOKING UTENSIL.

No. 914,216.

Specification of Letters Patent. Patented March 2, 1909.

Application filed October 24, 1906. Serial No. 340,378.

To all whom it may concern:

Be it known that I, THOMAS P. AITKIN, a citizen of the United States of America, residing at Manchester, in the county of Hartford and State of Connecticut, have invented 5 certain new and useful Improvements in Cooking Utensils, of which the following is a specification.

The object of my invention is to provide an 10 article of the class specified which has features of novelty and advantage.

Figure 1 is a front view of my cooking utensil. Fig. 2 is a sectional lateral view, 15 showing the broiler in place. Fig. 3 is a sectional plan view showing the rack.

This invention comprises an inclosing box *a*, on one wall of which there is pivotally supported a rack *b* which is adapted to receive the end of the broiler. This rack embraces 20 the sides of the broiler to prevent its slipping out edgewise. In a case where the broiler handle is round a notch in the opposite wall of the box will form a suitable support for the handle of the broiler. In a case where 25 the handle of the broiler is of wire, as is usual, I provide a plate *c* which is rotatably mounted in a suitable socket in the front of the box *a*, this plate being slotted as at *e* to receive the handle of the broiler. These supports 30 for the broiler in the front and rear walls of the box are arranged at such a height that the broiler can be continuously rotated in its support during the process of cooking, thus avoiding the necessity of lifting the broiler 35 to turn it or opening the box and letting the smoke out into the room.

The box as I make it is not of sufficient size to cover the entire opening in the top of the stove made by removing the lids so I provide 40 at each end of the box the flaps *g* which are adapted to be turned down to cover such openings in the top of the stove as are left outside of the box. A door *h* is provided through which the broiler is inserted, this door 45 being provided with a vision glass so that the process of the cooking can be watched.

The lower half *k* of the front wall of the box is hinged as at *k'* and in case the fire is low this front can be dropped down and the broiler 50 removed from the rack and lowered onto the bottom of the box, coming nearer the coals. By the use of such a box the smoke from the cooking is confined and carried off through the stove flues and the fire is protected so

that it will not die down as rapidly as when 55 the top of the stove is opened up.

I claim as my invention:

1. In a device of the character described, a box having a cover and provided with an opening in the bottom thereof, an elongated 60 rack rotatably secured to the rear wall of said box, a slotted plate rotatably-mounted in the front wall of the box in a plane with the rack, and a broiler having the rear end thereof received in and supported by said 65 rack and the handle thereof received in and supported by said slotted plate, the broiler rotatable in unison with said rack and plate and exposed at all times to the opening in the bottom of said box.

2. In a device of the character described, a box having a cover and provided with an opening in the bottom, an elongated rack 70 rotatably secured to the rear wall of said box, a broiler having its rear edge received in said elongated rack and revolvable in unison therewith and having its handle end supported in the front wall of the box, the 75 broiler being at all times exposed to the opening in the bottom of the box.

3. In a device of the class described, a box having a cover and provided with an opening in the bottom thereof, an elongated supporting member rotatably secured to the rear wall of the box, a broiler having its rear 80 edge received in and held by said supporting member and its outer or handle end rotatably mounted in the front wall of the box, the said broiler at its rear end being supported throughout its width by said supporting 85 member, the lower portion of the front wall of said box being hinged to the bottom of the box whereby said broiler may be removed from its supports and mounted upon the bottom of the box directly over the opening 90 in said bottom.

4. In a device of the character described, an inclosing box having a cover and comprising end walls, front and rear walls, and a bottom provided with an opening, the lower 100 portion of said front wall being hinged to said bottom whereby said hinged portion of the front wall may be lowered into a plane with the bottom, hinged flaps carried by said end walls, and means for rotatably supporting a broiler from the front and rear walls of the box, the said supporting means for the inner or rear end of the broiler comprising a 105

member separate from the broiler and rotatably secured to the rear wall of the box to rotate in unison with the broiler and being elongated in form to receive the rear end of the broiler to support the latter throughout its width.

5. In a device of the character described, an inclosing box, having a closed top and an open bottom and having the lower portion 10 of the front wall thereof hinged to be lowered into a plane with the said bottom, and a broiler rotatably supported by the front and rear walls of said box and exposed at all times to the open bottom of the box, said

support for the rear end of the broiler being 1 rotatably secured to the rear wall of the box and rotating in unison with the broiler and elongated in form to support the broiler throughout its width, the said broiler being 20 removably mounted in said rear support and having its outer or handle end removably mounted in the front wall of the box.

In testimony whereof I affix my signature in presence of two witnesses.

THOMAS P. AITKIN.
